UNITED STATES PATENT OFFICE.

MIRON G. REYNOLDS, OF ANDERSON, INDIANA.

FLUID-PRESSURE REGULATOR.

1,098,172.

Specification of Letters Patent. Patented May 26, 1914.

Application filed June 20, 1912. Serial No. 704,828.

To all whom it may concern:

Be it known that I, MIRON G. REYNOLDS, a citizen of the United States of America, residing at Anderson, in the county of Madison and State of Indiana, have invented certain new and useful Improvements in Fluid-Pressure Regulators, of which the following is a specification.

This invention relates to certain new and useful improvements in fluid-pressure regulators and more particularly to improvements upon my former Patent #746,879 granted December 15, 1903, the object being to improve the general construction of valve casing and to provide an outlet within the casing in order to allow the cover to be removed without disturbing the pipe system, whereby the interior of the regulator can be readily reached.

Another object of my invention is to improve the construction of valve lever and manner of mounting the valve block in order to prevent rotary movement thereof.

Another object of my invention is to provide novel means for fastening the valve block to the adjusting screw in order to allow a universal movement thereof so as to form a perfect seat upon the valve seat.

Other and further objects and advantages of the invention will be hereinafter set forth and the novel features thereof defined by the appended claims.

In the drawings—Figure 1, is a central vertical transverse section through the regulator; the outlet pipe being shown in elevation; Fig. 2, is a detail enlarged view of the valve lever and valve block partly in section, showing the manner of mounting the same; and Fig. 3, is a section taken on the line 3—3 of Fig. 2, showing the construction for preventing rotary movement of the valve.

Like numerals of reference refer to like figures in the several figures of the drawings.

In carrying out my improved invention, I employ a regulator casing 1 which is provided with an extended recess portion 2 having a suitable inlet opening 3 provided with a valve seat 4. The casing is also provided with a drain outlet 5 closed by a plug 6 and a vent in which is arranged a vent-pipe 7. A cover 8 is secured on the casing by any suitable means, and disposed between the casing and cover is a flexible diaphragm 9 which may be of any of the constructions now in use, which carries a plate 10 upon its upper surface and a bracket 11 upon its un-

der surface which is carried by a screw 12 extending through the plate 10 and diaphragm 9, as clearly shown in Fig. 1. The cover is provided with a central chamber 13 in which is arranged a coil spring 14, which bears at its lower end upon the plate 10 over the screw 12, and the upper end of the spring is engaged by an adjusting screw 15 threaded into the apertured portion of the chamber 13, all of which is substantially the same as shown in my former patent.

An inlet pipe is arranged within the inlet 3 and the extended recessed portion 2 is provided with a threaded boss 17 at right angles to the inlet and in which an outlet pipe 18 is secured, extending to the desired point. The cover of the casing is provided with a threaded boss 19 in vertical alinement with the inlet in which is arranged a threaded plug 20 which can be removed to facilitate the adjusting of the adjusting screw carrying the valve block as will be later described, which allows the valve block to be adjusted without removing the cover.

Arranged over the extended portion 2 of the casing 1 is a bridge 21 which is maintained in proper position by the cover in the same manner as disclosed in my former patent, said bridge having depending spaced ears 22 carrying a pivot pin 23 on which is pivotally mounted the enlarged bearing portion 24 of a valve lever 25, which is provided with an apertured end 26 pivotally mounted upon a pin 27 carried by the arms of the bracket 11, so that the valve lever will be rocked as the diaphragm expands and contracts. The opposite end of the valve lever 25 is provided with a vertically threaded bore 28 in which is mounted an adjusting screw 29 having at its lower end a neck portion 30 provided with a conical head 31 which is secured within a cylindrical seat 32 formed in the valve box 33, by swaging the wall of the block, as shown at 34, whereby the head 30 is held within the socket in such a manner that a universal movement is obtained so as to allow the block to seat itself upon the valve seat 4 of the inlet and in order to provide means for closing the inlet, I form the valve block 33 with a circular recess 35 in its bottom, in which is arranged a valve or washer 36, which co-acts with the seat 4 so as to completely close the same.

By this construction, the valve block is connected to the adjusting screw in such a manner that the same is free to rock in

order to form a perfect closure for the inlet, and at the same time the same can be secured in position upon the adjusting screw easily and quickly and in such a manner that

5 all danger of the same becoming accidentally detached is prevented.

In order to provide means for preventing the valve block from rotating upon the conical head, I cut away the upper portion 10 of the same to form a flat face 37, which is adapted to co-act with a shoulder 38 formed on the valve lever 25 in such a manner that the valve is free to rock but is prevented from rotating.

15 From the foregoing description, it will be seen that I have provided a fluid-pressure regulator in which the valve block is mounted in such a manner upon the valve lever, that a universal movement is obtained 20 without allowing rotation. It will also be seen that I have overcome the difficulty of my former patent by connecting the outlet pipe directly to the casing, at right angles to the inlet, in order to allow the cover and 25 working parts of the regulator to be removed without disturbing the pipeline, to which the regulator is attached. It will also be seen that I have provided means for reaching the interior of the regulator by 30 simply removing a plug screw in order to adjust the adjusting screw carrying the valve block.

I claim:

35 1. In a fluid-pressure regulator, the combination with a valve operating lever, of an adjusting screw carried by said lever, a valve block carried by said screw and having universal movement thereon, said block be-

ing provided with a flat face and a shoulder formed on said valve lever co-acting with 40 the flat face of the valve block for preventing rotary movement thereof.

2. A fluid-pressure regulator having a pivotally mounted valve lever provided with a threaded bore, an adjusting screw mounted in said bore having a neck at its lower end terminating in a conical head, a valve block provided with a socket to receive said head and secured thereon by swaging the head of said socket into the neck of said 50 screw, said valve block being provided with a flat face, and a shoulder formed on the valve lever co-acting with said face for preventing rotary movement of said block in respect to said screw. 55

3. A gas governor comprising a diaphragm, a lever pivoted to said diaphragm, a pivot for said lever, a screw adjustably inserted downward through one end portion of said lever, a valve seat, a valve hung on the lower end of said screw, having a rocking and rotative connection therewith, adapted to engage said seat, and means independent of said screw, for engaging the lower portion of said lever, disposed on the 60 side of the valve toward the pivot, to hold the valve against rotation, but permitting adjustment of said screw to change the operative position of said valve on said lever. 65

In testimony whereof I affix my signature in presence of two witnesses.

MIRON G. REYNOLDS.
